UNITED STATES PATENT OFFICE.

CALVIN R. WAID, OF BIRMINGHAM, ALABAMA.

SEGMENTAL GRATE-BAR.

1,306,729.

Specification of Letters Patent. Patented June 17, 1919.

Application filed August 16, 1918. Serial No. 250,210.

To all whom it may concern:

Be it known that I, CALVIN R. WAID, a citizen of the United States of America, residing at Birmingham, in the county of Jefferson and State of Alabama, have invented 5 certain new and useful Improvements in Segmental Grate-Bars, of which the following is a specification.

This invention relates to grate bars which 10 are composed of segments so designed that they can be readily assembled and interlocked upon a common supporting element and which will permit broken segments to be replaced without requiring the removal or 15 renewal of the whole grate bar.

The chief object of my invention is to 20 simplify and perfect the manner of mounting the grate bar segments upon a common support which is preferably in the form of a single bar which the bases of the segment 25 straddle and to which they are interlocked. When segments are damaged or broken blank repair segments can be inserted at any point or points and provision is made for locking such repair segments in place at any 30 point on the bar without delay or expense.

It is a further object of my invention to 35 cast the segments so that all drilling and machine work is reduced to a minimum both in the supporting bar and segment bases as the end segments will carry the trunnions for the grate bar and alone are keyed or bolted to the end of the supporting bar. The bar as initially assembled will have its 40 segment bases interlocked by lugs or bosses which will prevent the displacement of intermediate segments after they are assembled in position and the end segments are made fast to the bar. This improved manner of assembling the bar avoids the use of side straps and bolts such as are necessary in the grate bars described in my Letters Patents Nos. 1,151,746, 1,175,094, and 1,195,301. The repair segments and 45 preferably all segments underhang the bar so that alining and registering notches in the abutting faces of their bases will form holes through which keys or bolts can be inserted so as to pass under the supporting bar and 50 permanently lock repair segments in place after insertion.

My invention further comprises the novel details of construction and arrangements of parts, which in their preferred embodiments

only are illustrated in the accompanying 55 drawings, in which:—

Figure 1 is a side view of a grate bar with 60 its intermediate section broken away and with a blank segment inserted and secured in place.

Fig. 2 is a sectional view taken on the line 2—2 of Fig. 1.

Fig. 3 is a plan view of a standard intermediate segment.

Similar reference numerals refer to similar parts throughout the drawings.

As illustrated, the grate bar comprises end segments 1, standard intermediate segments 2, blank repair segments 3 and shaker arm segments 4. All of these segments are provided with similar fire heads 5 which may be of any suitable design or shape for the duty required of the grate in question but which preferably have the surface curvature shown. The bases 6 of the end segments 1 70 have cast thereon a laterally extended trunnion 7. Below the trunnion the base is provided with a vertical slot 8 opening through its bottom and having parallel side walls spaced to receive and fit snugly over the 80 bar 9 forming the main supporting element on which the segments are assembled. The base of each end segment has opposite holes 10 provided in its center and adapted to receive a key 11 which passes through the adjacent end of the bar and secure the end segment permanently in place thereon. The base preferably extends substantially below the lower edge of the bar and in its lower portion on each side I provide alining semi-circular key grooves 12, these grooves being provided on both side faces of the base. The inner side of the end segment bases which are wider than the fire heads are provided with downwardly sloping top surfaces 13 and in its inner side face each has a boss 14 on one side and a receiving recess 15 on the other side.

The standard intermediate segments 2 are provided with side bases 16 which come flush 100 overhead with the lower adjacent edge of the surfaces 13 on the end segments 1 and which are provided with the slot 10 and the semi-circular key grooves 12 disposed to register with each other and the like grooves on the 105 end segments. The side faces of the standard segment bases are provided with the bosses 14 and receiving recesses 15 on each

side, the bosses on the opposite sides being diagonally disposed. The bases for the repair segments 3 are similar in every respect to the standard segments except they are 5 devoid of the bosses 14 and may be cast that way or their bosses may be chipped off. In like manner the segments 4 are similar to the standard intermediate segments except that one side of the base extends downwardly to 10 form a shaker connection 16 which is offset from one side so that the adjacent segment 4 will have the proper space for the invention between the two connections of the connecting bar 17 which is secured to the shaker 15 connections by a bolt 18 passing therethrough and through the bar.

In assembling the bar initially one end is keyed on the bar and the intermediate segments are then mounted and shifted into 20 interlocked relationship by the engagement of the bosses of each in the receiving recesses of the two adjacent segment bases. The shaker segments 4 are inserted at the proper place and finally the other end segment is 25 mounted and keyed in position so as to hold all the segments securely interlocked by their bosses between the end segments. The bar is thus held assembled by means of only two end bolts. In the event a segment be 30 comes damaged or broken it is removed preferably by splitting its base and the bosses on the two adjacent segments which project into the cavity left by the removal of the damaged segment are chipped off, or 35 they may be replaced by segments free of such bosses. Then a blank segment can be inserted by dropping it over the bar 9 and it is locked in place by the insertion of cotter keys or bolts through the holes formed 40 by the registering key grooves 12 on each side of the repair segment. When thus interlocked, the key or keys prevent the upward removal of the repair segments and hold all the grate segments locked on their 45 supporting bar.

While I consider it desirable to have the several standard segments designed to depend below the supporting bar and carry the side key grooves 12, yet it should be understood that this is not essential as in the event 50 of the breakage of a segment the broken segment and the two adjacent standard segments may be removed and three blank repair segments inserted and interlocked to 55 each other by two cotter keys inserted through the holes formed by their registering grooves 12.

After one blank repair segment has been inserted this can be again easily removed to

permit the insertion of standard segments 60 needed to replace other broken segments in the same bar.

My bar is capable of ready assembly and of easy repair; is practically devoid of any machine work and can be made up of standard bars and a minimum number of stock parts.

Having thus described my invention, what I claim as new and desire to secure by Letters Patent, is:—

1. In a segmental grate bar, a bar, a plurality of grate segments having bases slotted to straddle and project below said bar, there being alining registering notches in the abutting faces of adjacent segments adapted to 75 form holes disposed below the bar, and keys adapted to be inserted through said holes and to pass under said bar to tie the adjacent segment bars thereon.

2. In a segmental grate bar, a bar, a plurality of grate segments having bases slotted to straddle and project below said bar, there being alining registering notches in the abutting faces of adjacent segments adapted to form holes disposed below said bar, keys 85 adapted to be inserted through said holes and to pass under said bar to tie the adjacent segment bars thereon, and means to fasten the end segments on said bar.

3. In a segmental grate bar, a bar, a plurality of grate segments having bases mounted on said bar and provided with bosses and recesses adapted to interlock on abutting bases, a blank segment free of bosses and having a base slotted to straddle and project below said bar, and a locking key inserted between said blank segment base and an adjacent segment and passing under said bar to lock the blank segment thereon.

4. In a segmental grate bar, a bar, a plurality of grate segments having bases mounted on said bar and provided with bosses and recesses adapted to interlock on abutting segment bases, a plurality of segments, one of which is free of bosses on both sides and 105 the adjacent two of which are free of bosses on one side, said latter three segments having their bases projecting below said bar, there being alining registering notches in the abutting surfaces of said three segments 110 below the lower level of said bar, and locking keys inserted through said registering notches to hold said three segments assembled on the bar.

In testimony whereof I affix my signature. 115
CALVIN R. WAID.
